whereby a hairpin assembly is formed from a single strip of resilient stock material, the upper leg being bent upwardly and outwardly to form a loop, the lower leg being bent downwardly and inwardly to form a loop, the two legs being joined together at their outer ends to form a hairpin, the upper leg being bent upwardly and outwardly at its outer end to facilitate insertion of the hairpin into the hair, and the lower leg being bent downwardly and inwardly at its outer end to facilitate withdrawal of the hairpin from the hair.

UNITED STATES PATENT OFFICE

2,566,782

HAIRPIN

Mirabeau C. Towns, Jr., Sparta, N. J.

Application March 21, 1949, Serial No. 82,661

2 Claims. (Cl. 132—50)

1

This invention relates generally to hairpins, and more particularly to an improved hairpin of the bobby pin type which may be readily used with either hand alone and which cannot turn in the hair nor tear the hairs.

In the past, many attempts have been made to provide hairpins of various sorts which would be susceptible of ready manipulation during the process of pinning up the hair. However, the known hairpin devices of the bobby pin type are generally characterized by a number of real disadvantages which make them impractical in use and hence, unpopular with the trade.

Among the above disadvantages are: a difficulty in separating the legs of the hairpin preparatory to its insertion in the hair resulting in broken finger nails and even marred teeth; a tearing of the hair strands by the material forming the hairpin from the hair; a turning of the hairpin while in place so as to render hair dressing inaccurate as to planned style; and a general difficulty in manipulation of the hairpin at all times due to its small size and the high degree of finger dexterity required to avoid a fumbling of the hairpin during use.

Accordingly, the chief object of the present invention is to provide an improved hairpin which obviates the aforementioned disadvantages of prior art structures.

Another important object of the invention is to provide a hairpin which may be readily manipulated with only one hand by a person of ordinary finger dexterity or less.

A further important object of the invention is to provide a hairpin which is so constructed as to prevent its turning after being placed in the hair and which will indicate by touch to the user whether the hairpin is right side up or not so as to enable its ready use without visual inspection or even in the dark.

A still further important object of the invention is to provide an unusually efficient hairpin of the bobby pin type in which the cooperating legs are so shaped as to prevent tearing of the individual hairs and yet permit the hairpin to be withdrawn from the hair by simply pulling the hairpin therefrom.

Another object of the invention is to provide a hairpin which is of simple though rugged construction, neat in appearance, and inexpensive to manufacture.

Other objects and advantages of the invention will become readily apparent during the course of the following description.

In the drawings, I have shown one embodiment of the invention. In this showing:

Figure 1 is a perspective view of the invention illustrating its ready manipulation with a single hand;

Figure 2 is a view in side elevation of the invention;

Figure 3 is a top plan view thereof;

Figure 4 is a horizontal sectional view taken on the line 4—4 of Figure 2, parts being shown in plan;

Figure 5 is a vertical sectional view to an enlarged scale, taken on the line 5—5 of Figure 2; and

Figure 6 is a vertical sectional view to an enlarged scale of the invention, taken on the line 6—6 of Figure 2.

Referring to the drawings, the invention comprises a long strip of resilient stock material, preferably metal, bent to form a loop 10 and a pair of legs 12 and 14. The upper leg 12 is of greater length and bent upwardly and outwardly as at 16 to facilitate the insertion of the hairpin in the hair as will become apparent.

An important feature of the invention resides in the fact that the stock from which the hairpin is formed is slightly convex on the inner surface and slightly concave on the outer. As seen in Figures 2, 5 and 6, the legs 12 and 14 are tightly in contact throughout their lengths by means of the crowns of their respective convex or inner surfaces. Moreover, the corners of the stock, top and bottom, have been rounded, as at 18, so as to completely eliminate all sharp edges so that the hairpin is incapable of tearing individual hairs during its insertion or removal.

It is to be noted that the convexity of the inner surfaces of the legs 12 and 14 is such that while a maximum of clamping action is obtained at the crowns or central portions, the remaining portions of the surfaces also function in this manner although to a slightly lesser degree. Accordingly, the clamping function is fully maintained by the hairpin while it is unable to tear or injure the individual hairs.

Another important feature of the invention resides in the provision of a widened portion in the lower leg 14 at its outer end. This widened leg portion comprises a pair of oppositely projecting wings 20 and 22 which are preferably integral with the leg 14 to enable the hairpin as a whole to be readily formed from the same sheet of stock.

The wing 20 has the same lateral dimension but is longer than the wing 22 in order that the user may instantly determine by comparative touch whether the hairpin is right side up or not. This is extremely advantageous to women.

as they may rapidly put up their hair without having to glance specifically at each hairpin used and further enables them to use the hairpins efficiently in poor light or even in the dark as is often required of them.

It is to be noted that the wings 20 and 22 continue the degree of convexity of the leg 14 (enlarged in Figure 5) so that the contour of the head is followed and the hairpin is allowed to lie in the hair snugly against the user's head in an inconspicuous manner. More important, the wings 20 and 22 have a stabilizing effect and prevent any tendency of the hairpin to turn in the hair and thus prevents accidental misplacement of set curls, etc.

It will now be readily apparent that the hairpin comprising the present invention may be readily manipulated and requires but ordinary, or less, dexterity of the fingers. Without looking at the source of supply, the user may hold a curl with one hand and reach for and easily grasp a hairpin by its wings 20 and 22 with the other hand.

If using the right hand, the thumb should engage the side of the shorter wing 22 while the second finger engages the side of the wing 20. If the hairpin is not picked up in this position, the fact will be readily apparent to the touch by the difference in length of the wings and the hairpin is thereupon turned right side up.

Holding the hairpin in the described position, the loop 10 will engage the palm of the hand. The index finger is now extended to engage the end 16 of the upper leg and by exerting pressure away from the thumb and second finger, the legs 12 and 14 are readily separated and placed in position in the hair. The hairpin is removed from the hair by simply pulling it therefrom without danger of pulling or injuring the individual hairs due to the rounded surfaces and corners of the invention.

It is to be noted that this important feature, the provision of a practical hairpin which requires the use of only one hand, is accomplished in a hairpin of conventional size except for the wings. The latter are of minimum size to avoid a space problem in marketing but of sufficient size to enable the hairpin to be readily grasped for the purposes stated.

Thus the hairpin comprising the present invention is especially suitable for putting up the hair with one hand without damaging the finger nails, their polish or the teeth as the legs are so readily separable due to the wing construc-

tion which also indicates, without the presently required inspection, whether it is right side up or not. Moreover, the wings ensure the coiffure intended by preventing turning of the hairpin in the hair with an ensuing loosening or misplacement of curls, etc. Injury to the hair by the hairpin therein or being removed therefrom is prevented by the mating convex surfaces and their rounded edges.

It is to be understood that the form of my invention herewith shown and described is to be taken as a preferred example of the same and that various changes in the shape, size and arrangement of parts may be resorted to without departure from the spirit of the invention or the scope of the subjoined claims.

I claim:

1. A hairpin comprising a strip of resilient material bent to form a long leg and a short leg in contacting engagement, said short leg being of substantially greater width than said long leg adjacent its end to form a pair of finger engaging wings to facilitate the manipulation of said hairpin, one of said wings being of greater length than the other to indicate the relative vertical position of said legs.
2. A one-handed hairpin comprising a strip of resilient material bent to form a long leg and a short leg in contacting engagement, and means engageable by the thumb and second finger for effecting a separation of said legs when the forefinger urges the end of the long leg away from said short leg comprising a pair of laterally projecting wings formed on said lower leg adjacent its end, one of said wings being of greater length than the other to indicate the relative vertical position of said legs.
